[57] CLAIM

The ornamental design for a knee support and pad, as shown.

DESCRIPTION

FIG. 1 is a front elevational view of a knee support and pad, showing our new design;

FIG. 2 is a rear elevational plan view thereof;

FIG. 3 is a right side elevational view thereof;

FIG. 4 is a left side elevational view thereof;

FIG. 5 is a top plan view thereof; and,

FIG. 6 is a bottom plan view thereof.

The broken line showing of environment in FIGS. 1 and 2 is for illustrative purposes only and forms no part of the claimed design.
